UNITED STATES PATENT OFFICE.

GIUSEPPE CALAMIELLO, OF PATERSON, NEW JERSEY.

SHOE CONSTRUCTION.

1,217,703.

Specification of Letters Patent. Patented Feb. 27, 1917.

Application filed April 12, 1916. Serial No. 90,646.

To all whom it may concern:

Be it known that I, GIUSEPPE CALAMIELLO, a subject of the King of Italy, residing at Paterson, in the county of Passaic and State 5 of New Jersey, have invented certain new and useful Improvements in Shoe Construction, of which the following is a specification.

This invention relates to new and useful 10 improvements in shoe construction.

The primary object of the invention is to provide an improved form of heel construction and sole plate secured together and upon which rubber or leather tread sections 15 are secured.

Another object of the invention is to provide an improved form of heel construction, in which the major portion of the heel is formed of a wooden block or similar material 20 incased in a metal shield and carrying an exposed tread section of flexible material.

With these general objects in view and others that will appear as the nature of the 25 invention is better understood, the same consists in the novel combination and arrangement of parts hereinafter fully described, illustrated in the accompanying drawing and then claimed.

30 In the drawing forming a part of this application and in which like designating characters refer to corresponding parts throughout the several views:—

Figure 1 is a side elevational view of a 35 shoe constructed in accordance with the present invention, and partly shown in section to illustrate the construction of the heel portion.

Fig. 2 is a top plan view of the heel and 40 sole section united and detached from the shoe upper.

Fig. 3 is a cross sectional view taken on line III—III of Fig. 2.

Fig. 4 is a horizontal sectional view of 45 the heel taken on the line IV—IV of Fig. 1, and

Fig. 5 is a detached detail perspective view of a portion of the sole plate adjacent the heel portion.

50 Referring more in detail to the accompanying drawing, the reference numeral 10 designates a shoe upper that may be of any suitable construction and having attached thereto the sole section 11 either of rubber 55 or leather and the heel section 12.

The sole section 11 is connected to the

upper 10 by the metallic plate 13 extending about the periphery of the sole 11 and provided with a plurality of apertures 14 for the passage of threads in sewing the plate 13 to the upper 10 as in the lasting operation. The sole plate 13 is of skeleton form while the rear portion thereof is of increased cross sectional area, as is indicated at 15 in Figs. 1 and 5, while the rear end thereof 60 is formed with a flat face 16 having openings 17 therein and depending corner lugs 16' for purposes presently to appear.

The heel section 12 includes an outer metallic shell having an upper flat wall 18, 70 the side and rear walls 19 and the front wall 20 having openings therein registering with the openings 17 when the heel section 12 and sole section are juxtaposed as is shown and in such position rivets 21 passed through 75 the aligned openings secure the parts together. Any suitable means may be employed for securing the heel casing 12 to the upper 10.

In order to cheapen the construction of 80 the shoe, the major portion of the heel is formed of a wooden block, the wooden block 22 being received within the casing 18 and retained therein as by the screw 23 passing downwardly through the upper wall of the 85 casing and engaging in the block, and also by the lugs 16' carried by the sole section, which lugs are rearwardly bent at right angles as shown in Fig. 1 to be positioned beneath the wooden block 22 which will 90 further hold the block in position. A rubber or tread section 24 is provided for the heel and has enlarged openings 25 on the 95 tread surface thereof which will permit the reception of enlarged heads upon retaining nails 26 employed for fastening the tread section 24 upon the block 22.

From the above detailed description of the construction of the device, it is thought that the operation will be readily apparent, 100 and while I have shown and described what is believed to be the preferred embodiment thereof, it is nevertheless to be understood that minor changes may be made in the form, proportion and details of construction 105 without departing from the spirit and scope of the invention as hereinafter claimed.

What I claim as new is:—

A shoe comprising an upper, a sole plate 110 permanently secured thereto, a sole tread connected to the sole plate, the rear end of the sole plate being of increased cross-sec-

tional area and presenting a vertical rear wall and a curved front wall, depending lugs carried by the opposite corners of the lower edge of the rear end of the sole plate, 5 a heel section including a casing having a flat front wall in engagement with the rear wall of the sole plate, means for permanently securing the abutting walls together, a wooden block within the heel casing, a

screw carried by the casing for retaining 10 the block therein, the said lugs adapted to be bent rearwardly at right angles to engage said block further to hold the same in position, and a tread lift secured to the wooden block.

15

In testimony whereof I affix my signature.

GIUSEPPE CALAMIELLO.

Copies of this patent may be obtained for five cents each, by addressing the "Commissioner of Patents, Washington, D. C."
